(57) **CLAIM**

The ornamental design for an exit device cover, as shown and described.

DESCRIPTION

FIG. 1 is a top, front, right side perspective view of an exit device cover showing my new design;

FIG. 2 is a top, front, left side perspective view thereof;

FIG. 3 is a bottom, back, left side perspective view thereof;

FIG. 4 is a front elevation view thereof;

FIG. 5 is a top plan view thereof;

FIG. 6 is a bottom plan view thereof;

FIG. 7 is a right side elevation view thereof;

FIG. 8 is a left side elevation view thereof; and,

FIG. 9 is a back elevation view thereof.

The broken lines in the drawing figures depict portions of the exit device cover that form no part of the claimed design.

1 Claim, 6 Drawing Sheets
